UNITED STATES PATENT OFFICE.

WILLIAM J. YEOELL, OF PHILADELPHIA, PENNSYLVANIA, ASSIGNOR TO JOHN STOGDELL STOKES, OF PHILADELPHIA, PENNSYLVANIA.

PRINTING-PLATE AND METHOD OF MAKING THE SAME.

1,379,430.

Specification of Letters Patent.

Patented May 24, 1921.

Application filed August 12, 1913. Serial No. 784,456.

To all whom it may concern:

Be it known that I, WILLIAM J. YEOELL, of Philadelphia, Pennsylvania, have invented certain Improvements in Printing-Plates and Methods of Making the Same, of which the following description, in connection with the accompanying drawings, is a specification, like characters on the drawings designating like parts.

5 10 This invention relates to the art of printing, and the present case is directed to improvements in molded printing plates and method of making the same.

15 The matrix structure and method of making the matrix herein described forms the subject matter of divisional application of the present case, filed December 2, 1920, Serial No. 427833.

20 In the manufacture of a printing plate embodying the present invention I use a plastic substance in the nature of a synthetic resin, such as a phenolic condensation product, as I have found that this material is exceedingly well adapted for my purpose, 25 inasmuch as a printing plate having a phenolic condensation product as a constituent possesses certain manifest advantages over stereotypes, electrotypes, and other forms of printing elements now in use. For example,

30 this plastic material may be readily molded to exact dimensions, and is capable, under the molding operation, of accurately reproducing the finest details of an original type form or of the matrix employed. Furthermore 35 after the phenolic condensation product, under the action of heat and pressure, has undergone chemical reaction and assumed its usual final, hard and substantially infusible form, it provides a structure of

40 great strength and durability, which is capable of resisting stresses, strains and shocks incident to handling, transportation, and printing operations. In addition such a structure is not affected by acids or other 45 cleansing fluids generally used in printing offices for cleaning the type, and will have but a fraction of the weight of metallic printing plates and may therefore be advantageously mailed because of the low rate of postage required.

50 Another advantage incident to the use of

phenolic condensation product in the manufacture of my plate is that the latter may be molded, and therefore finished in much less time and with fewer operations than 55 required for the production of printing plates by the electrotype and kindred methods, and consequently my plate may be produced with great economy from the standpoint of time and labor.

60 It is also my purpose to provide a molded printing plate comprising, in a unitary structure, a replication of original printing characters as widely different as type and half tone plates.

65 I also propose to provide a simple, efficient and economical method through the practice of which large quantities of my plates may be produced with a minimum expenditure of time, labor and cost.

70 With the above recited objects and others of a similar nature in view, my invention consists in the improved printing plate and in the method of making the same set forth in and falling within the scope of the ap- 75 pended claims.

75 In the accompanying drawings:

80 Figure 1, is a plan view of a printing plate embodying a preferred form of my invention.

Fig. 2, is a view of the same in vertical section, on the line X²—X², Fig. 1.

85 Fig. 3, is a cross sectional view of a metal-faced matrix which is used in the production of the plate shown in Figs. 1 and 2.

Fig. 4, is a plan view, with parts broken away, illustrating the assemblage of the plate and matrix, and coöperating appliances at the time of molding a plate.

90 Fig. 5, is a cross sectional view taken on the line X⁵—X⁵, of Fig. 4.

Fig. 6, is a fragmentary, detail view, in vertical section, on the line X⁶—X⁶ of Fig. 4 and showing the final stage in the preparation of the plate-molding matrix.

95 Fig. 7, is a vertical sectional view taken through a type form and showing one of the preliminary steps of forming the matrix.

Fig. 8, is a view similar to Fig. 7 and showing another step in the formation of 100 the matrix.

Fig. 9, is a view in front elevation show-

ing conventionally a press and certain co-operative devices which may be used in producing my invention.

Fig. 10, is a vertical sectional view of a plate showing a sheet metal face thereon.

Fig. 11, is a view showing one manner of stripping a plate.

Fig. 12, is a cross sectional view of a modified form of plate.

Fig. 13 is a plan view, partially broken away, and showing a modified arrangement for producing the printing plate matrix.

Fig. 14, is a cross sectional view taken on the line X¹⁴—X¹⁴ of Fig. 13.

Fig. 15, is a plan view, partially broken away, and showing a modified arrangement for producing a printing plate.

Fig. 16, is a cross sectional view taken on the line X¹⁶—X¹⁶ of Fig. 15.

Fig. 17, is a cross sectional view showing a further modification in the manner of preparing a matrix for service in making the printing plate.

In the preferred form of my invention, as herein described, I make the body of the printing plate of a synthetic resin, such as a phenolic condensation product, and provide such body with a printing face or impression producing surface of metal, thereby providing a composite printing element which will have the advantages above mentioned as incident to the use of the phenolic condensation product, and at the same time will possess desirable attributes of a metal printing plate.

Before entering into a detailed description of my invention I will briefly state that I first prepare a matrix having a metal molding face preferably formed by pressing or swaging a metal sheet against a body of type, half tone, etching, or a combination of these, thus producing in the metal face sheet characters complementary to the printing characters of the original type form. I then use this metal-faced matrix for molding my printing plate which, in its preferred form, has a metal printing face as above mentioned. The printing plate may be made in a number of ways as by coating the molding face of the matrix with a suitable material having a metalliferous content, for example a paste containing powdered zinc, and thereafter applying the phenolic condensation product in suitable form to the coated surface of the matrix and applying pressure and heat until the phenolic condensation product has been molded to the desired contour and the metal coating metallized or reduced to a smooth, homogeneous sheet-like form, thus providing a metal printing face incorporate with or formed on the hard phenolic body, the the resultant printing face being in all respects a negative replica of the matrix. Instead of forming the metal face of the

printing plate of a metallic paste I may make the same of a homogeneous sheet of metal; and the phenolic condensation product constituting the body of the plate may be applied in any preferred or well-known commercial form, for example either as a powder or as a sheet, as in whatever form this product may be used the heat and pressure of the molding operation will transform it into a hard and set and substantially infusible sheet-like body and will intimately unite the same with the metal face.

For the preferred form of my invention reference will first be made to Figs. 1 to 9 inclusive.

The complete printing plate as illustrated in Figs. 1 and 2 embraces a body or base 1 of a non-metallic material such as a phenolic condensation product having a metallic face 2 which in the present instance contains a reproduction of letters, shown at 24' and of a half tone as shown at 25, thus constituting a printing surface.

The matrix which I prefer to use in molding this printing plate is best shown in Fig. 3, and as illustrated comprises a metal sheet 4 having type forming depressions or intaglios 44 formed therein and separated by the convexly rounded interstitial webs or reliefs 46.

The metal sheet 4 is also preferably formed adjacent its marginal edges 40 with the marginal beads 41. The metal sheet 4, as thus formed constitutes the molding face 100 of the matrix and is backed with a layer of fibrous material, such as blotting paper, as shown at 27. This fibrous material is impregnated with a shellac or varnish as indicated at 29, and the exposed face of 105 this sheet 27 is coated and leveled with a layer of hardened plastic material, such as plaster of Paris or the like, as shown at 16.

In making this metal-faced matrix I proceed as will best be understood by reference to Figs. 7 and 8. I provide a type form 22 carrying the original printing element to be reproduced, such as a printing plate 23. This original printing plate may be made up, for example, of letter characters 24 which will ultimately be reproduced in the letters 24' of the molded printing plate shown in Fig. 1, and the original plate may also contain a half tone which will ultimately be reproduced in the half tone printing surface section 25 of said molded printing plate. Upon the original form thus constituted I place the metal sheet 4 which is to be manipulated to form the molding face of the matrix. This sheet 4 115 may be in the nature of a thin layer of steel, brass, zinc, or other suitable metal which is capable of being rolled or forced into the interstices of the original to be reproduced. Upon the metal plate 4 I then place 120

a blanket of felt or other suitable material as shown at 26, and back this with a sheet of harder material such as a smooth, calender cardboard indicated at 28. The parts 5 thus assembled as shown in Fig. 7 are then passed through a suitable roll press, such as shown at 30 in Fig. 9, with the result that the metal sheet 4 will be rolled or pressed into the original plate 23. The 10 roller press 30 in the present instance is actuated by a belt 32 from a shaft 34 driven by suitable source of power (not shown).

The matrix thus partially produced is now ready for the next step in its formation. 15 This step consists in sharpening the definition of the intaglions or depressions of the matrix, as it is upon the clearness of these that the printable quality of the molded plate to a great measure depends. To effect 20 this sharpening of the intaglions or type-forming depressions of the matrix face I remove the felt blanket 26 and the cardboard 28, and substitute therefor the fibrous sheet or blanket 27, impregnated with a 25 sharpening medium such as varnish or shellac, as shown at 29, and as heretofore mentioned. The metal matrix sheet 4 is of course still upon the original type form.

The parts, assembled as shown in Fig. 8, 30 are now passed through the roller press 30 with the result that the sheet or blanket 27 will draw the thin sheet of metal 4 more closely over and into intimate relation with the corners of the printing characters of the 35 original plate, thus reproducing faithfully all of the details and printing characteristics of the original plate 23. In addition to producing every salient characteristic of the original plate the matrix face will be found 40 to have convexly rounded webs 46 in place of the usual square spaces between type characters, so that there will be no crevices in the matrix to catch and tear material molded thereagainst, and this matrix face 45 will furthermore lend itself to the ready coating with metalliferous paste or the like which may be used for making the metal face of the molded printing plate.

Following this second passage of the 50 metal matrix face 4 through the roll press it will be found that the fibrous sheet or blanket 27 has been rolled or pressed into the back of the metal sheet, and this fibrous sheet 27 is permitted to remain to constitute 55 a support for the metal face 4 and a constituent part of the complete matrix. I prefer to then apply to the exposed back of the fibrous sheet 27 a layer of plastic material shown at 16, which may be composed 60 of plaster of Paris for example, and which may be leveled and hardened to form a coating or back face for the complete matrix.

For the purpose of hardening, leveling and finishing the matrix after it has been 65 coated with the plastic material 16, by the

means of a knife or brush, I may employ the apparatus shown in Figs. 4, 5 and 6. This apparatus, which is in the nature of a molding box, comprises a base plate 80, preferably of copper, carrying two rectangular frames, one imposed upon the other, and each formed of an L-shaped normally stationary section and an L-shaped shiftable section reversely positioned relative to the companion stationary section, together with 70 short, removable connecting strips dovetailed with and connecting the companion sections of each frame. The stationary section of the lower frame is shown at 48, the shiftable section at 78, and the dovetailed 80 connecting strip at 77. The stationary section of the upper frame is shown at 58, the shiftable section thereof at 98 and the connecting strip at 87, the dovetailed joints being indicated by the numerals 97. The upper frame is undercut to receive the lower frame, and to provide the depending shoulder 68 as shown in Figs. 5 and 6. Dowel pins 19 secure the stationary frame sections 48 and 58 to each other and to the base 80, 90 and similar dowel pins also connect the shiftable sections of the upper and lower frames, as well as their dovetailed connecting strips to each other and to the base. 95 When the box is to be used for a double column plate or matrix, for example, it will appear as shown in Fig. 4 with the dovetailed connecting strips in use and forming parts of the frame. But when a single column article is to be accommodated, for example, the dowel pins of the shiftable frame sections and the connecting strips are pulled out, such connecting strips removed, and the frame narrowed by moving the shiftable sections toward their companion stationary 100 sections until the companion frame sections are in contact, when a relatively narrow frame will be provided as will be readily understood. The dowel pins may then be replaced in the shiftable sections to hold the latter against movement. A movable abutment bar 71, preferably of steel, is provided, and has at its upper end an overhang 72 with a pin 73 adapted to enter a selected hole 74, of a series of holes arranged along 115 the adjacent edge of the base 80. The lower end of the bar has a similar overhang 75 with a set-screw 76 which can be selectively set in any one of a corresponding series of holes 79 along the bottom edge of the base 120 80. The abutment bar 71 affords a rigid support against outward lateral displacement of the shiftable frame members, and is operated in an obvious manner, by loosening the set-screw, shifting the bar from one 125 set of holes to another, and then again tightening the set-screw.

The upper frame member is provided with a series of abutment blocks 91 working in sockets 92 and tensioned by the springs 93 130

which normally thrust the upper portions of the blocks above the top face of the frame. The purpose of these blocks will be herein-after described.

5 In leveling and finishing the matrix, the latter along with the original plate 23 is placed with the plastic back 16 of the matrix in contact with the waxed surface 88 of the base plate 80, the wax being employed 10 to prevent the adherence of the plastic to the plate. In this position the original plate 23 is uppermost, as shown in Fig. 6. The frames of the molding box are adjusted and fastened so that the lower frame will confine 15 the matrix against lateral movement while the upper frame, through the shoulder 68 will rest upon and clamp the matrix against vertical movement. A plunger or pressure block 11 is then applied, with the recess 12 of the plunger receiving the original plate 23 and the concave flange 13 of such plunger resting upon the matrix face adjacent the marginal edge portion thereof. The parts thus assembled, as indicated in Fig. 6, are 20 now ready for the action of a press. Any suitable press may be used, and in Fig. 9 I have shown one apparatus, comprising a hydraulic press 50 having a piston 52 working in a cylinder 54 connected by a conduit 25 56 with a pump 60 driven by the belt 62 running to the shaft 34. The press is preferably provided with a suitable pressure indicator 57 and a controller 51, and I also provide suitable means for heating the press, 30 such for example as a steam boiler 70 heated by the gas burner 72^a. The boiler is provided with a water inlet 74^a, a safety valve 75, a pressure gage 76^a and a conduit 77^a, for leading steam to the hollow head 59 of 35 the press 50, this conduit having a controlling valve 78^a. The numeral 53 designates the bed platen of the press while 55 is a table which may be conveniently located adjacent to and in front of the press. The matrix assembled in the molding box, as before described is placed upon the platen of the press and the controller 51 operated to admit hydraulic pressure from the pump 60 through the conduit 56 to the cylinder 54, 40 which forces the piston 52 and the platen 53 upward until the plunger 11 of the molding box contacts with the press head 59 and is forced downward into the upper mold frame until the latter contacts with the press head 45 thereby limiting the extent to which the plunger can compress the matrix, the buffer or abutment blocks 91 being depressed into their sockets by contact with the press head. The pressure of the concave flange of the 50 plunger 11 against the metal face of the matrix will produce a standardizing marginal bead 41 upon the latter, as the fiber sheet 27 at the back of the matrix face tends to force the metal of the latter upward into the

groove 13 of the plunger head, under the 85 pressure exerted. This marginal bead will always occupy the same position regardless of the extent of the characters 44, so that when the printing plate material is forced against the matrix bead in the operation of 70 molding the printing plate, as illustrated in Fig. 5, the plate will be given a concave marginal depression which serves as a guide to the operator in trimming the plate to the exact width desired and to form the marginal edges of the plate as shown at 7 in Fig. 1.

The matrix may be subjected to a suitable degree of temperature and pressure for desired length of time to produce the necessary leveling and baking or finishing of such matrix. For example with the steam pressure of about 100 to 150 pounds in the boiler I can secure temperatures of from 200° F. and upward on the press 50, while a corresponding hydraulic pressure of say from 500 pounds to 2500 pounds in the cylinder 54 will give satisfactory results, the time required to bake the consolidated material varying from 2 to 15 minutes, in correspondence with the degrees of pressure and heat attained. When the matrix has been properly baked and leveled the piston is lowered, the base plate 80 withdrawn with the frame members and the matrix, and after these parts have been placed on the table in front of the press the plunger 11 and the original plate 23 are removed to expose the molding face of the matrix 4.

When it is desired to make the molded 100 printing plate shown in Fig. 1 the metal molding face of the matrix is provided with an additional coating or layer of metallic material. For example the matrix face is coated with a metalliferous paste as indicated at 5 by brushing or other means of application, and then a body of the phenolic condensation product, either in powder or sheet form is filled in to near the upper level of the upper frame of the molding box. Instead of using the plunger 11 in making the plate, I substitute therefor a plunger 10 which comprises a block or plate of metal having a series of spaced V-shaped ribs 21 formed on its under surface. This plate is laid in position as shown in Fig. 5 with the V-shaped ribs projecting into the soft phenolic condensation product which at this time is in its plastic or non-reacted state. The molding box with the parts thus assembled as shown in Fig. 5 is again placed upon the lower platen or bed of the press and the latter is closed to exert the necessary pressure, while at the same time heat is applied for a desired period and at a pre-determined temperature so that simultaneously, with the molding of the plate the phenolic condensation material of the latter will un- 110 115 120 125

dergo the well-known reaction to assume a hard and set form. As in the operation of making the matrix, the baking of the printing plate can be accomplished in a period 5 varying from 5 minutes, or even less, to about 15 minutes, according to the conditions of heat and pressure found desirable for different materials, a pressure from 500 to 2500 pounds in the press, and a steam 10 heating pressure of from 100 to 150 pounds being satisfactory in general, with a corresponding temperature ranging from 200° F. upward. The action of heat and pressure in the molding operation will cause the metallic 15 alliferous paste to assume a smooth, hard and homogeneous or sheetlike form and to intimately incorporate or unite with the phenolic condensation product forming the body of the plate, and at the same time the molding 20 face of the matrix, even to the finest detail, will be accurately and faithfully reversely duplicated or reproduced to form the printing face of the plate as shown in Fig. 1 for example. Incidentally the V-shaped ribs 21 25 of the plunger 10 resting against the back of the plate will produce in the latter V-shaped grooves 12^a, as shown in Fig. 2, which will make the plate lighter than if the rear surface were continuous, and this 30 interruption of the surface also permits the plate to be more readily leveled or brought to the desired contour.

The spring tensioned buffer or abutment blocks 91 when the press is closed will first 35 contact with the press head so that the frame members will be firmly clamped before any flow of the plastic material 6 can begin.

After the printing plate has been properly 40 molded and baked or hardened and set the press may be opened, and the base plate 80 with the assembled parts removed. Subsequently the plate may be cleared from the mold, trimmed and mounted for use in a 45 printing press, or, devoid of the mounting, it may be mailed to its ultimate destination and there mounted and used like any other printing plate, such as an electrotype. It may also be used in other reproductive processes, such as an original from which to 50 make mats for use in casting stereotypes.

It will be noted that the construction of the molding box is such that the plate may be readily removed from the matrix, without 55 disturbing the latter, this being accomplished by simply dismantling or opening the upper frame while permitting the lower frame of the molding box to remain in position and confining the matrix. Thus any 60 number of plates may be made without taking the matrix from the molding box.

If, in exceptional instances, the metallic matrix face 4 should adhere to the metal face 2 of the molded printing plate, the op-

erator can readily strip off the sheet 4 as 65 indicated in Fig. 11, thus clearing the metal surface 2 for printing purposes.

In some instances, it may be desirable to leave the sheet metal face 4 permanently in place upon the printing plate 1, this providing a sheet metal printing surface, as is shown in Fig. 10, but under ordinary circumstances I prefer to form the metallic printing face of the molded plate as heretofore described. 75

In Fig. 12 I have illustrated a modified form of printing plate wherein the body portion 101 of non-conductive material, wholly, or chiefly, is provided with a metallic printing surface 102 formed by the 80 electrodeposition of zinc 103 upon one or both sides of a metal foil 104, indicated in the drawings by black line. The zinc layers are shown of exaggerated thickness for the sake of clearness. The zinc 103 may be, 85 and preferably is deposited upon the foil 104 prior to the application of the latter to the form, the sheet thus provided having the advantages of softness and ductility when employed for plates of large size, a 90 printing surface composed thereof presenting the printing qualities of the original form of type and it also possesses the concave interstitial web portions 126.

The several steps employed in the production of my improved plates may be modified to suit various conditions. For example, referring to Figs. 13 and 14, I may first make a matrix by imposing a mold frame 180 upon the margins 40 of the matrix 100 molding face 4 which in Fig. 14 is shown in contact with the body of type 240 locked in the chase 220, the metal face 4 being backed by the fibrous blanket 27 as before described. I then fill the space within the confines of 105 the walls of the frame 180 with a backing material 160 of powder or sheet form and place a suitable plunger 11^a above the same. The parts thus assembled are placed in the press and there compressed to consolidate 110 the backing 160 and preferably bake the same, as heretofore described with respect to the strengthening material 16.

The assembled parts, with the plate 80 may then be removed from the press, using 115 the handle 81, and then re-arranged as shown in Figs. 15 and 16 with the frame 180 reversed and imposed upon the base plate 80, containing plunger 11^a, backing 160, blanket 27 and metal matrix face 4 in the order 120 named, with the margins 40 of the matrix face extended over the frame 180 and the intaglios 44 presented upwardly. Thereupon the upper section 188 of the mold frame, is superimposed upon the margins 40 125 of the matrix face sheet 4, the latter then provided with a coating 5 of metalliferous paste, as already described, and the plate

blank material 106, in powdered or sheet form, is introduced into the cavity of the mold frame member 188, the plunger 10 placed in position, and the parts thus assembled are again compressed in the press 50 to mold and set the plate after which the parts may be dismantled and the now molded printing plate removed as heretofore described. Of course the plate blank 10 material is molded and set under heat and pressure as has been heretofore mentioned.

In Fig. 17 I have shown still a further modification in preparing the matrix for the printing plate. In this instance the numeral 15 45 indicates a metal sheet forming the molding face of the matrix, while 46 indicates the original form or plate imposed upon the metal sheet 45. Within the mold frame 18, resting upon the base plate 80, is placed a 20 bed or body of backing powder, the wax 88 preventing the adherence of the powder to the plate 80. The metal sheet 45 carrying the original form or plate 46 is placed in contact with the backing powder, with the 25 marginal edges 49 clamped between the frame 18 and the frame 38. A plunger block 90 is now inserted within the frame 38 and the parts thus assembled are subjected to heat and pressure, as through the 30 agency of the press shown in Fig. 9, to complete the formation of the matrix. When the matrix is thus backed, it is only necessary to remove the plunger 90 and the original form or plate 46, when the intaglio side 35 of the matrix will be exposed within the frame 38 in position ready to be coated with the metalliferous paste and to receive the plastic phenolic condensation product for the formation of the body of the printing 40 plate 1. This arrangement provides a very rapid operation or succession of steps in making the printing plate.

In connection with my invention it will be noted that I have provided a pressed-up or molded printing plate comprising in a 45 unitary structure a replication of original printing characters as widely different as type and half-tone plates, an achievement, which, so far as I am aware, has not been attained heretofore in molding printing plates 50 for the reason that the original half-tone surface presents interstices of but slight depth between its "dots" over extended areas, while type and line cuts, on the contrary, present large areas of considerable 55 depth between the lines making up their printing characters and it has been practically impossible to press up a unitary plate from these diverse surfaces for the reason 60 that the pressure requisite to force the material into the type original must be applied differently from that used in forcing the material of the plate into the half-tone original.

By making the metal matrix face as herein 65 described and backing the same with the fibrous blanket treated with a sharpening medium I am enabled to secure with equal pressure, in the matrix face, a duplication 70 of both half-tone and type or line characters, and then I can produce from this matrix, with equal pressure, a molded printing plate embodying in a unitary structure both line and dot surfaces, and of equal thickness throughout their extent. 75

What I claim is:—

1. A printing plate comprising a laminated body composed of layers of different materials, one of said layers comprising a hard, set and substantially infusible reacted 80 plastic, one face of the laminated body having printing characters thereon to constitute a printing face.

2. A printing plate comprising a laminated body composed of a layer of hard and set synthetic resinous material, and a layer of non-resinous material, one face of the laminated body having printing characters thereon to constitute a printing face. 85

3. A printing plate comprising a metallic 90 face provided with printing characters and an infusible hard cementitious back united with and supporting the printing face.

4. A printing plate comprising two united layers, one of a hard synthetic resin and the 95 other of metal, one of said faces being provided with printing characters to constitute a printing face.

5. A printing plate having a body portion 100 consisting wholly of non-metallic material and having a metallic printing surface incorporate therewith.

6. A printing plate having a body portion of a phenolic condensation product with a metallic printing surface incorporate therewith. 105

7. A printing plate comprising a body portion of non-conducting material, and a face of metal forming a homogeneous layer 110 and integrated with the body portion.

8. A composite printing plate having a unitary metal printing surface comprising a pressed-up replication of both line and dot printing characters.

9. A composite printing plate comprising 115 a hard body of synthetic resin and having a printing face composed of a pressed-up replication of both line and dot printing characters united with the body portion.

10. As an article of manufacture, a printing plate comprising a sheet-metal printing face provided with impression producing printing characters, and a backing sheet of a hard resinous product united in integral formation with and supporting the sheet-metal face. 120

11. A printing plate comprising a sheet-metal impression producing face provided

with printing characters, and a backing sheet composed of a synthetic resinous material adherently united with and supporting the sheet-metal impression producing plate.

5 12. A printing plate having a layer-like body of relatively hard phenolic condensation product having a series of inverted V shape grooves formed in the back face thereof and extending in parallelism between opposite edges of the plate.

10 13. A printing plate having a layer-like body of a synthetic resin having a series of substantially parallel grooves formed in the back face thereof and having its front face provided with printing characters to form the printing face.

15 14. The herein described method which comprises impressing a body of type against a metallic sheet to provide the latter with a metallic plate-molding face, then placing a body of plate forming material including a plastic synthetic resin against the metallic molding face and subjecting the same to heat and pressure to form a printing plate.

20 15. The herein described method which comprises impressing a type body against a metallic sheet to provide the latter with a metallic plate-molding face, then placing a body of plate forming material including phenolic condensation product in contact with the molding face and then subjecting the same to heat and pressure to form a hard infusible printing plate readily separable from the molding face.

25 16. The herein described method of making a printing plate which consists in placing a composite sheet, including a metallic facing sheet and a cementitious backing sheet, against the molding face of a matrix having printing characters therein with the metallic facing sheet in contact with such molding face of the matrix, and applying heat and pressure to reproduce in the metallic facing sheet characters complementary to the printing characters of the matrix, and to cause the cementitious backing sheet to assume a hardened and set form.

30 17. The herein described method of making a printing plate which consists in placing a composite sheet, including a facing sheet and a cementitious backing sheet, against the molding face of a matrix having printing characters therein with the facing sheet in contact with such molding face

of the matrix, and applying heat and pressure to reproduce in the facing sheet characters complementary to the printing characters of the matrix, and to cause the cementitious backing sheet to assume a hardened and set form.

35 18. The herein described method of making a printing or embossing plate which comprises molding printing characters in a metallic impression producing face sheet having a cementitious backing sheet, and hardening and setting the cementitious backing sheet under heat and pressure.

40 19. The process of producing printing plates, which comprises: subjecting to prolonged high pressure at high temperature against a suitable form a plastic having therein means for effecting hardening of the plastic under heat, and a prepared thin sheet of metal adapted to be united with the plastic in an integral structure and afford a metal facing affording a working surface provided with reliefs and depressions.

45 20. The herein described method of making a printing plate which consists in placing a suitably prepared sheet of metal and a cementitious backing sheet against the molding face of the matrix, with the metal sheet in contact with such molding face of the matrix, and applying heat and pressure to produce in the sheet-metal facing characters complementary to the characters of the matrix and to cause the cementitious backing sheet to assume a hardened and set form and be permanently united to the sheet-metal facing.

50 21. The method of making a laminated printing plate which comprises placing a layer of plastic synthetic resinous material in contact with a layer of non-resinous material, and subjecting the two layers to heat and pressure against a matrix to form a printing surface on the laminated body, to unite the two layers, and to convert the synthetic resinous material to a hard and substantially infusible form.

55 Signed at New York in the county of New York and State of New York this twenty-third day of July, 1913.

WILLIAM J. YEOELL.
